SAFETY DEVICE FOR MOTOR DRIVEN WRINGERS

Filed Dec. 20, 1921

By Lancaster and Morris
Attorneys

UNITED STATES PATENT OFFICE.

FREDERICK SCHAU, OF HAMMOND, INDIANA.

SAFETY DEVICE FOR MOTOR-DRIVEN WRINGERS.

Application filed December 20, 1921. Serial No. 523,712.

To all whom it may concern:

Be it known that I, FREDERICK SCHAU, a citizen of the United States, residing at Hammond, in the county of Lake and State 5 of Indiana, have invented certain new and useful Improvements in Safety Devices for Motor-Driven Wringer, of which the following is a specification.

This invention relates to attachments for 10 clothes wringers and the primary object of the invention is to provide an improved guard for the power driven clothes wringers of washing machines, which is so constructed that the easy feeding of the clothes 15 in between the wringer rolls is permitted but the possibility of the user's fingers becoming entangled in the rollers is prevented.

Another object of the invention is the provision of a clothes wringer embodying a 20 pair of spaced guard plates, which prevents the feeder's fingers from becoming entangled in the rollers and serves as means for guiding the clothes in between the rollers.

A further object of the invention is to 25 provide an improved guard for power driven clothes wringers embodying a lower stationary guard plate and an upper pivoted guard plate, the plates being disposed relatively close to each other so as to eliminate the 30 possibility of the user's fingers being caught between the wringer rollers, the plates being connected together in such a manner that the space between the plates can be regulated according to the character 35 of the clothes which are being wrung.

A still further object of the invention is to provide an improved guard for clothes wringers of the above character which is durable and efficient in use, one that is simple and easy to manufacture, and one which 40 can be placed upon the market at a reasonable cost.

With these and other objects in view, the invention consists in the novel construction, 45 arrangement and formation of parts as will be hereinafter more specifically described, claimed and illustrated in the accompanying drawings, forming a part of this specification, in which drawings:

50 Figure 1 is a side elevation of a washing machine including a power driven clothes wringer showing the improved guard attached thereto.

Figure 2 is a front elevation of a clothes wringer showing the improved guard applied thereto. 55

Figure 3 is an enlarged fragmentary vertical section through a wringer in which the wringer rollers thereof are adapted to be driven only in one direction, showing the 60 improved guard attached thereto.

Referring to the drawings in detail, wherein similar reference characters designate corresponding parts throughout the several views, the letter A indicates a washing machine, B, the power driven clothes wringer therefor, and C, the improved guard attachment utilized for preventing the feeder's fingers from becoming entangled with the rollers. 70

The washing machine designated by the letter A may be of any preferred type and is of the ordinary construction, and the wringer B is operatively connected thereto in the usual manner and includes the supporting side pieces or standards 5 and the upper and lower wringer rollers 6 and 7. The wringer rollers 6 and 7 are adapted to be operated in the usual manner. 75

In Figure 1 the improved guards C are shown connected to the opposite sides of a clothes wringer and in this form the wringer rollers are adapted to be driven in reverse directions according to the relation of the wringer with the washing machine and with the ordinary stationary or other washing tubs. 80

In Figure 3 only one of the guard members C is shown connected to the wringer B and in this instance the wringer rollers are 90 adapted to be only driven in one direction and are not reversible.

The improved guard device C as shown includes a lower inclined plate 8 which is connected to the standards or side pieces 5 by means of brackets or the like 9 and it can be seen that these brackets are secured to the lower surface of the plate adjacent to its opposite ends and extend downwardly therefrom and are connected to the side edges of the standards. As stated, this plate 8 is inclined downwardly and away from the standards and serves as means for guiding the clothes to and away from the rollers and this plate is positioned at a point substantially intermediate the upper and lower roll- 95 100 105

ers 6 and 7 or at a point adjacent to the upper edge of the lower roller 7. An upper plate 10 is arranged directly above and in relatively close relation to the plate 8 and this plate 10 is normally positioned in a horizontal plane and is positioned slightly above the lower surface of the upper wringer roller. The position of the plate 10 is such, in relation to the plate 8 and to the rollers 6 and 7, that the pushing of the feeder's fingers into and between the rollers 6 and 7 is absolutely prevented.

The upper plate 10 is connected to the side standards or pieces 5 by suitable hinges 11 and these hinges may be of any preferred construction or arrangement just so the same permits of the swinging of the upper plate in relation to the lower plate 8.

The board 10 is held in its correct position in relation to the board or plate 8 by means of bolts 12 which are positioned adjacent to the opposite ends of the upper and lower plates 10 and 8. The lower plate 8 is provided with apertures 13 through which the shanks of the bolts 12 extend. The plate 10 is provided with relatively large openings or slots 14 through which the upper terminals or threaded ends of the bolts 12 extend. The coil springs 15 are coiled around the shanks of the bolts and bear against the upper and lower plates respectively and normally hold the plate 10 in its raised position. Suitable wing nuts 16 are threaded on the upper threaded terminals of the bolts 12 and bear against the upper surface of the plates 10 and serve as means for adjusting the tension of the springs 15 and for moving the board or plate 10 toward the lower plate 8.

Thus it can be seen that by turning the thumb nuts 16 the tension of the springs can be adjusted and the position of the board 10 moved in relation to the lower board or plate 8. This serves as means for varying the distance between the two boards so as to adjust the guard in accordance with the nature of the clothes which are being washed.

In operation of the improved clothes wringer and guard, the clothes are pushed in between the boards or plates 8 and 10 in the ordinary manner and these plates will serve as guides for facilitating the feeding of the clothes between the wringer rollers

6 and 7 but will act as guards for preventing the fingers of the user from becoming entangled between the rollers. 55

From the foregoing description it can be seen that an efficient guard of simple and durable character has been provided for power driven clothes wringers which will absolutely preclude the possibility of the fingers of the user from becoming mashed by the rollers and will serve as means for helping to guide the clothes into engagement with the wringer rollers. 60 65

If so desired a stick or other instrument may be utilized for feeding the clothes in between the rollers and for pushing the same between the plates 8 and 10. 70

Changes in details may be made without departing from the spirit or scope of this invention; but, 75

I claim:

1. In a clothes wringer, the combination with the side standards and upper and lower wringer rollers thereof, of a guard for the wringer rollers including an inclined outwardly extending plate, means connecting the plate to the standards, a second plate located above and adjacent to the first plate, means hingedly connecting the upper plate to the standards, spaced bolts connecting the plates together and arranged adjacent to the forward edges of the plates, supporting springs coiled around said bolts and interposed between said plates, and means for adjusting the tension of said springs for varying the distance between the forward edges of the plates. 75 80 85 90

2. In a clothes wringer, the combination with the side standards and the upper and lower wringer rollers thereof, of a guard for the wringer rollers including a transversely extending inclined guard plate, side brackets 95 engaging the lower surface of the guard plate and connecting the guard plate with the standards, said plate terminating at a point adjacent to the meeting faces of the rollers, an upper plate arranged adjacent to and spaced from the guard plate, means hingedly connecting the inner edge of the upper plate to the side standards, and means connecting the forward edges of said plates for holding the same in spaced relation to 100 each other and varying the distance between the forward edges of said plates. 100 105

FREDERICK SCHAU.
